Hanson & Hanson.

UNITED STATES PATENT OFFICE.

ROBERT M. GREEN, JR., OF PHILADELPHIA, PENNSYLVANIA, ASSIGNOR TO ROBERT M. GREEN & SONS, OF PHILADELPHIA, PENNSYLVANIA, A FIRM COMPOSED OF ROBERT M. GREEN, JR.

SODA-WATER DRAFT.

Application filed July 21, 1921. Serial No. 486,457.

To all whom it may concern:

Be it known that I, ROBERT M. GREEN, Jr., a citizen of the United States, residing in Philadelphia, Pennsylvania, have invented 5 Soda-Water Draft, of which the following is a specification.

The present invention relates to a soda water draft used for dispensing carbonated water, and one of the objects of said invention is to provide a device of this character in which the volume and speed of the stream of carbonated water discharged may be controlled by a simple and easy movement of the operating handle in a single 15 plane and in a single direction.

A further object of the invention is to provide a soda water draft in which there are a plurality of valves controlling the speed and volume of the water and whose 20 construction shall be such that they may be operated by a single movement of the operating handle; the device including means for insuring the proper seating of the main valve and for preventing subsequent leakage.

I also desire to provide novel means for holding the operating handle in one of its displaced positions to permit a continuous flow of the water, and which retaining 30 means may be readily released when the flow of water is to be restricted or entirely cut off.

Another object is to provide a soda water draft with a novel arrangement of fluid passages and valves, which will operate to cause a gradual cutting off of the flow of water.

These objects and other advantageous ends, I attain as hereinafter set forth, reference being had to the accompanying drawings, in which.

Fig. 1 is a vertical sectional view of a soda water draft constructed in accordance with my invention; and

Figs. 2 and 3 are vertical sections similar to that of Fig. 1, showing the operating parts in positions to deliver a large slow stream and a fine rapid stream respectively.

In the above drawings, 1 indicates a pipe 50 leading from a carbonated water tank and threaded into a part 2 of the draft apparatus. An opening 4 permits communication between the pipe 1 and the interior of the draft apparatus, and a needle valve 3 55 is mounted within the portion 2 in position

to be projected across the opening 4 to restrict or regulate the flow of water to the draft apparatus. The needle valve 3 is threaded into a suitable sleeve 5, which is in turn threaded into the part 2.

The inlet portion 2 carries at its opposite end a fixed casing 6, having a partition 6^a and containing the valve for controlling the discharge of carbonated water. Said partition has an axial passage of which one part 6^b is slightly smaller in diameter than a second part 6^c, and its opposite faces are shaped to form valve seats 6^d, 6^e. The upper end of the casing 6 is closed by a removable cap 7 and is surrounded by an 60 outer movable casing 8 having openings 9 in its lower face. The inlet portion 2 projects through a slot 10 in the casing 8 and this slot is of a length sufficient to permit movement of said casing while said portion 2 and the inner casing 6 remains stationary. The upper end of the casing 8 is closed by a threaded cap 11, having an axial opening 12 in which is mounted a hollow flanged plug 13 whose body closely fits 70 and projects out of the smaller portion 12^a of the opening 12. The upward movement of the plug is limited by the flange 13^a.

A plug 14 is threaded into the lower portion of the opening 12^b and its lower face 85 abuts upon the upper face of the cap 7 when the parts are in the inoperative positions shown in Fig. 1 so that it acts as a stop for the outer casing 8. By adjusting the plug 14 up or down, the position or rest of 90 the casing 8 may be regulated as desired.

A coil spring 15 is mounted within the plug 13 so as to act between it and the plug 14 and to normally project said plug 13 through the top of the cap 11 to the 95 limit permitted by the flange 13^a.

An operating handle 16 with a head 16^a has two arms 17 with forked lower ends 17^a mounted on pivot pins 18 projecting from the outer casing 8. These arms 17 have rear extensions 17^b pivotally mounted upon a pin 19 carried by a projecting portion of the part 2.

A screw 20 is mounted in the operating handle 16 between the arms 17 in position 105 to engage the top surface of the plug 13 when said handle is in its inoperative position (Fig. 1) and upon movement of the handle from the position of Fig. 1, said screw will disengage the plug 13, which will 110

be projected outwardly through the cap 11 to the position shown in Figs. 2 and 3.

If it is desired that the operating handle remain in the discharge position of Fig. 2, the operator may remove his hand and the screw 20 attached to the handle will be retained against the plug 13. When the handle is moved towards its normal position, the screw 20 will ride upon the plug 13 and force it downwardly against the action of the spring 15.

Within the casing 6 is a check valve 21 having a body portion 21^a surrounded by a coiled spring 23 which maintains it in proper vertical alignment and the lower face of said valve is recessed for the reception of a washer 22 adapted to cooperate with the valve seat 6^a surrounding the upper end of the passage 6^b. A screw 24 is threaded into the valve 21 and has a head 24^a formed with a transverse slot 24^b.

A poppet valve 25 has a stem 25^a loosely movable within the passage 6^c and formed to closely fit the passage 6^b; its upper end being convexly curved and designed to cooperate with the slotted face of the screw head 24^a. The valve 25 is flanged approximately midway of its length and the upper face of the flange has a recess for a packing 30 washer 26 positioned to engage the valve seat 6^e formed around the lower end of the passage 6^c. The lower end of the valve 25 is of reduced diameter and projects through an opening 28 in the bottom face of the outer casing. A shoulder 25^b on the lower end of the valve, rests upon the inner surface of the lower edge of the casing, to limit the downward movement of the valve 25, and also to transmit movement to it from the outer casing. A passage 29 is formed through the center of the valve 25 and has a restricted portion 30 at its lower end.

Under normal conditions the parts are in the inoperative positions shown in Fig. 1, with the valve 21 seated on the valve seat 6^a closing the passage 6^b and the valve 25 in its lowest position with its shoulder 25^b resting on the bottom end of the casing 8. When it is desired to deliver carbonated water, the handle 16 is moved from the position of Fig. 1 to that shown in Fig. 2, causing an upward movement of the outer casing 8 and of the valve 25. During such upward movement the stem 25^a will engage the screw 24 of the valve 21 and cause an upward movement of the latter against the action of the spring 23, thereby moving said valve 21 from its seat 6^a and opening the passage 6^b. Carbonated water will now flow from the inlet 4 through the passages 6^b and 6^c around the stem 25^a and out through the delivery openings 9. The operating handle may be allowed to remain in the position

shown in Fig. 2 with the full flow of water discharging, since the screw 20 engages the retaining plug 13. This arrangement is particularly advantageous when a continuous flow of water is desired without the necessity of the attendant holding the operating handle.

When a sufficient flow of water has occurred, and it is desired to deliver a fine fast stream, the operating handle is moved to the position shown in Fig. 3 thus causing a further upward movement of the outer casing 8 and of the valve 25. During such further upward movement the stem 25^a will raise the valve 21 further from its seat, and the upper end of said stem 25^a will enter and thus close the passage 6^b, preventing flow from around the outside of the stem 25^a.

When the parts reach the positions of Fig. 3, the washer 26 is seated upon the valve seat 6^e, and since the slot 24^b in the head of the screw 24 is immediately adjacent the upper end of the passage 29, a limited amount of water will pass through said slot into said passage, through the restricted passage 30 from which it will be delivered in a fine fast stream. When it is desired to entirely cut off the flow of water, the operating handle is moved to the position of Fig. 1, whereupon the screw 20 rides upon the top of the plug 13 and forces it into the cap 11. During such movement the outer casing 8 and the valve 25 will move outwardly while the valve 21 will close the passage 6^b.

It has been found in prior apparatus of this character, where the valve was directly connected to an operating means, or where the valves 21 and 25^c were made integral, that the valve 21 would not properly seat, and would cause leakage at this point. This is entirely overcome in the present construction.

By the provision of a rounded face upon the upper end of the valve stem 25^a, there will be a gradual closure of the passage 6^b and consequently a gradual cutting off of the water.

I claim:

In a soda water draft, the combination of a casing, valve means therein for causing the delivery of fine or coarse streams of water, automatic means tending to actuate said valve means to prevent the discharge of water, a handle movable to either of two positions to actuate said valve means, and means for temporarily retaining said handle in a position in which the valve means permits delivery of a coarse stream comprising a spring-pressed plug mounted in said casing independent of the valves and adapted to engage a portion of said handle.

ROBERT M. GREEN, JR.
